H. J. MOREY,
ELECTRIC LAMP SOCKET CASING,
APPLICATION FILED APR. 16, 1914.

1,191,812.

Patented July 18, 1916.

UNITED STATES PATENT OFFICE.

HARRY J. MOREY, OF SYRACUSE, NEW YORK

ELECTRIC-LAMP-SOCKET CASING.

1,191,812.

Specification of Letters Patent. Patented July 18, 1916.

Application filed April 16, 1914. Serial No. 832,292.

To all whom it may concern:

Be it known that I, HARRY J. MOREY, a citizen of the United States, residing at Syracuse, Onondaga county, New York 5 State, have invented certain new and useful Improvements in Electric-Lamp-Socket Casings, of which the following is a specification.

This invention relates to casings for electric lamp sockets and the like, and has particular reference to improvements in the cap portion of the casing.

The principal object of my invention is to eliminate insulating joints between the 15 socket and the fixture to which the same is attached and is especially suitable for use on bath room fixtures and similar locations.

The above and other objects and the novel 20 features of my invention will be apparent from the following description taken in connection with the drawing, in which,

Figure 1 is a side elevation showing a 25 socket embodying my invention as it appears when attached to a fixture; Fig. 2 is a plan view of the cap portion of a casing embodying my invention; Fig. 3 is a bottom plan view of the same; Fig. 4 is a cross section of the cap embodying my invention, taken on the line 4—4 of Fig. 2; and Fig. 5 is a cross 30 section of the cap taken on the line 5—5 of Fig. 2, showing the upper end of the casing as it appears when interlocked with the cap, and showing the connection of the cap to the fixture.

Referring to the drawing, the socket, the lamp attached thereto, and the inclosing casing for the socket are shown as supported from the side wall 10 by means of a fixture 11 which consists in the present case of a 40 curved piece of brass tubing which is provided with threads 12 at its outer end. The casing for the socket 8 and insulating lining 9 carrying the switching mechanism and lamp terminals of any preferred design consists of a cap to be more fully described and a tubular shell 14 of the usual construction which has a slot (not shown) extending 45 downwardly from its upper end to receive the spindle carrying the key 15, by means of which the switching mechanism on the interior is operated. The socket 8 on the interior has lamp terminals to receive and hold an incandescent lamp 16. At its upper edge the shell 14 has a plurality of corrugations 50 17 and also has horizontal and vertical latching lips, a horizontal latching lip being

shown at 18. The construction of the shell is not new and is substantially like that shown in the patent to G. W. Goodridge, No. 958,626.

The cap comprises a block 20 of insulating material, such as porcelain, which is provided at its center with an opening 21 flaring downwardly and at opposite sides of the center has recesses 22 to receive the angular lugs 60 which are integrally connected to a ring 24, which has a large number of symmetrically arranged rectangular openings 25. The openings 25 are closed on the outside by a brass ring 26 which has a narrow interior 65 flange 27 fitting and supported by a shoulder 28 on the ring 24 and has its lower edge spun inwardly as at 29 under the lower edge of the inner ring 24. The inner and outer rings telescope over the upper edge of the 70 shell 14 and the latching lips on the latter engage in the openings 25 of the inner ring 24 and detachably lock the two parts together. It will be understood, however, that 75 my invention is not limited to the particular latching means shown and any desirable type of interlocking device between the cap and shell may be employed, one of the readily detachable type being preferable. The interlocking means herein shown is 80 fully described in the patent to Goodridge 85 above referred to.

The insulating block 20 is notched as at 30 to receive the end of the outer ring 26 and has an overhanging part 31 which is of 90 greater diameter than the attaching ring and extends downwardly and overlaps the upper end thereof. Each of the integral securing lugs on the attaching ring has an upwardly extending portion 32 and a horizontally extending portion 33, completely disposed within the recesses 22, 22 in the block 20. The screws 34 extend through openings in the horizontal parts 33 of the lugs and through partitions 35 into recesses 100 36 opening at the top of the block 20. The threaded screws are held in place by nuts 37 bearing on the partition walls 35 and the cavities 36 are then filled with suitable insulating material 38 to cover the metal parts. 105

A brass sleeve or nipple 39 having a central opening 40 provided with threads 41 to fit the threads 12 on the end of the brass tube 11 has integral ears 42 on diametrically opposite sides thereof at the lower edge, provided with threaded openings to receive the screws 43 which hold the sleeve 39 in place 110

on the block 20 and co-axial with the opening 21 of the block. The screws 43 are passed through openings 44 from the under side of the block 20 and the heads 45 of the screws rest on shoulders at the bottom of the screw cavities 44. In order to lock the sleeve in place on the end of the tube 11, I provide a pointed set screw 46 which extends through the wall of the sleeve. The ears 42 and the lower end of the nipple 39 are counter sunk so that the ears will be disposed flush with the top of the block 20.

It will be seen that I have provided a casing for a lamp socket or the like which may be attached to a metal support or other fixture and still be completely insulated therefrom, the block or separating member 20 constituting an insulating barrier between the metal parts surrounding the lamp socket and the nipple by means of which the shell is attached to the fixture. The usual insulating lining for the shell portion 14 of the casing may or may not be eliminated as preferred, but the construction of the cap does away with the insulating lining for the cap. The downwardly flaring opening 21 leaves sufficient room for bends in the incoming wires which are attached to the terminals on the lamp socket.

While I have shown and described my invention in detail, I do not wish to be limited to the exact construction shown as it is clear that numerous modifications may be made without departing from the spirit of the invention.

Having thus described the invention what I claim as new and desire to secure by Letters Patent is:

1. A cap of the class described comprising the combination of a block of insulating material having an opening extending centrally therethrough, and means whereby the

cap may be attached to a socket shell, said means comprising a ring having lugs for attaching the same to said block, and a second ring carried by the first mentioned ring and provided with means for interlocking with portions on the socket shell.

2. A cap of the class described comprising the combination of a block of insulating material having an opening extending centrally therethrough and also having recesses in the lower side thereof on opposite sides of said opening, and means whereby the cap may be attached to a socket shell comprising a ring having lugs secured in said recesses in the block, and a second ring carried on the inner side of said first mentioned ring and having a series of recesses adapted to receive portions of the socket shell to secure the cap to the shell.

3. A cap of the class described comprising a substantially cylindrical body of insulating material having a central opening extending therethrough, a nipple secured to the top of said body coaxially with said opening, and a device whereby the cap may be attached to a socket shell, said device having means uniting the same to the body of insulating material, said uniting means being located within the margin of said body.

4. A cap of the class described comprising a body of insulating material having a centrally disposed opening flaring toward the lower side, a nipple secured to said body above the opening and coaxially therewith, and means on the lower side of said body for attaching the cap to a socket shell.

In testimony whereof I affix my signature in presence of two witnesses.

HARRY J. MOREY.
